UNITED STATES PATENT OFFICE.

ALLEN D. ALFORD, OF DALLAS, TEXAS.

REAMER DRILL BIT.

Application filed December 6, 1926. Serial No. 152,787.

This invention relates to improvements in reamer drill bits and in such connection it relates more particularly to the novel arrangement and construction thereof.

Heretofore in rotary drills it was possible at times to underream the hole made by the bit by means of reamers which were projected by gravity from the drill stock or body. In such underreamers, however, as the reamer body was dropped in the drill body the reamers were projected a short and defined distance beyond the drill.

It is of importance in drilling when the cap rock is reached that the hole be enlarged into a well-defined chamber and it is to accomplish this purpose as well as to provide a tool for underreaming that the present invention has been devised.

In the present invention two reamer bits are provided, each bit being pivoted at its inner end to a cylindrical head, carried by the drill body, which head is recessed to receive the bits. The head is so arranged that it will move downward in the drill body by means of water, steam or air pressure, forcing the reamer bits outward at a more or less angular relationship to the drill body, and a coiled spring, co-acting with the pressure, is adapted, when the pressure is released, to cause the bits to resume a normal position in the head and drill body. Suitable means are employed to gauge the reamer bits to the distance they are to project outward before the pressure is applied.

With the above and other minor objects in view, the invention will be better and more clearly understood by reference to the following description, in connection with the accompanying drawings, and wherein:

Figure 1 is a view partly in section and partly in side elevation of a reamer drill embodying the main features of the invention.

Figure 2 is a vertical sectional view, illustrating more in detail the position of the spring and bits when the latter are fully extended.

Figures 3, 4, 5, 6 and 7 are cross-sectional views taken on lines 3-3, 4-4, 5-5, 6-6 and 7-7, respectively, of Figure 1; and

Figure 8 is an elevational view of a plug.

In the arrangement and construction of the invention there is provided a drill body 1 which is hollowed or interiorly chambered, the lower end being screw-threaded to re-

ceive a drill bit 2. Inside the drill body 1 are arranged the reamer bits 3-3, which are pivoted by a pin 4 to a hollow slideable head of which 5 indicates the top, and having a circular opening 5^a for the admission of water under pressure, the bottom or lower end indicated at 6 formed integral with a pin 7. This head is recessed to receive the reamer bits 3-3, the walls of the recess being shown at 5^b. The top 5 of the head and its bottom or lower end 6 have projections 8-8 formed integral therewith and fitting into a complementary groove or channel 9 and wherein the head rides when the bits are advanced outward, so that the reamer bits 3^a will not rotate within the drill body, but will turn with said body in reaming out the hole.

Referring again to the pin 4, to which the reamer bits are pivoted, it will be seen by reference to Figure 4 that these bits overlap each other, and the pin when fully advanced is enclosed in the drill body 1, its ends supported by the recess walls 5^b. When so advanced the holes in the drill body into which the pin 4 is inserted are closed or plugged by screws 4^a and 4^b.

Arranged to encircle the pin 7 is a coil spring 10, one end resting against the under side of the hollow head, the other end of the spring encircling a pin 11 and supported by the head 12 of the pin, which is screw threaded so that it may be advanced upward in the drill body 1. Between the head 12 of the pin 11 and the drill bit 2 is a space 13 to allow of sufficient room for the head 12 of the pin 11 to be moved up or down in the drill body 1.

To set or gauge the distance the reamer bits 3-3 are to project through the slots 3^a, there is provided a key 14 threaded to receive a circular nut 15. The key 14 is placed on the top 5 of the head and the key turned, forcing the head downward, the reamer bits being projected outward through the slots 3^a, the desired distance. The head 12 of the pin 11 is then advanced until the pins 11 and 7 meet. The key 14 is then removed.

When water pressure is used the water is forced downward through the drill stem 16, passing through the opening 5^a and thence through the openings 6^a and 12^a to clean the mud from around the spring, etc. Water can thus pass through the openings, yet the pressure is sufficient when thus diminished.

2
to hold the pin 7 and the pin 11 in contact and thus retain the bits in a rigid position for underreaming. When air or steam pressure is used the opening 5^a is closed by a suitable plug 5^c.

What is claimed is:

1. A reamer drill having a hollow cylindrical body, a drill bit on the end thereof, a 10
slidable head within the drill body, reamer bits carried by said head, said head having an opening in its top and a series of openings in its lower end to admit water under pressure, the lower end of said head formed integrally with a downwardly projecting 15
pin, a movable nut with an upwardly projecting pin below the upper pin, and a coil

spring encircling and resting on the shoulders of said pins.

2. A reamer drill comprising a hollow body, a drill bit on the end thereof, a 20
slidable recessed head within said hollow body carrying reamer bits, a coil spring below said head supported by a nut and pin, perforations through said head, nut and drill bit for the admission of water under pressure to thereby contract said spring and project the reamer bits outwardly at right angles to the drill body, and means for closing the opening in the top of said head when 25
applying steam or air pressure. 30

In testimony whereof I affix my signature.

ALLEN D. ALFORD.
